UNITED STATES PATENT OFFICE.

JOHN J. BROWN, OF NEW YORK, N. Y., ASSIGNOR TO HENRY R. WORTHINGTON, OF NEW YORK, N. Y., A CORPORATION OF NEW JERSEY.

CENTRIFUGAL, TURBINE, AND SIMILAR PUMP.

1,112,516.

Specification of Letters Patent.

Patented Oct. 6, 1914.

Application filed August 19, 1905. Serial No. 274,906.

To all whom it may concern:

Be it known that I, JOHN J. BROWN, a citizen of the United States, residing at New York city, county of Kings, and State of New York, have invented certain new and useful Improvements in Centrifugal, Turbine, and Similar Pumps, fully described and represented in the following specification and the accompanying drawings, forming a part of the same.

This invention relates to that class of centrifugal, turbine and similar pumps in which inclosed impellers are used, the object of the invention being to provide improved means for balancing the impeller and preventing end thrust.

Attempts have been made to avoid differences in pressure on opposite sides of the impeller and prevent end thrust by making the impellers so as to expose equal surfaces to the pressure in the spaces on opposite sides of the impeller into which the delivery liquid passes around the edge of the impeller. It is found in practice, however, that impellers so constructed are not balanced, and that it is difficult and expensive to provide satisfactory means for preventing the end thrust, because it cannot be determined before trial upon which side of such impellers the total pressure will be larger, it being practically impossible to secure in manufacture uniform running conditions in the spaces on the opposite sides of the inclosed impeller. Moreover, wear and other causes result in changes in these conditions during use, so that a pump in which, when new, the end thrust is a certain amount and in one direction, will change in amount of end thrust and may even have the end thrust in the opposite direction after considerable use. I avoid these difficulties and provide a pump in which the impeller or impellers can be balanced conveniently and efficiently, under all changes of running conditions, by making the impeller outside the running joint of larger radius on one side than the other, so that there shall be a constant excess of pressure on one side of the impeller in the side spaces, under all running conditions, and then oppose this constant excess of

pressure by a regulated pressure from an outside source, preferably by admitting water to a balancing chamber on the back of the impeller. I also preferably circulate this balancing liquid between the impeller bearing surfaces on the rear side of the impeller so as to secure to some extent the effect of a liquid bearing, and thus reduce largely the friction and wear in the pump.

In the accompanying drawings forming a part of this specification, the invention is shown as applied in its preferred form to a single impeller pump of a well-known type, and this construction will now be described, and the features forming the invention then be specifically pointed out in the claims.

Referring to said drawings, in which the pump is shown in vertical central section taken longitudinally of the axis, A is the pump casing having the suction B and delivery C, D the impeller carried by the shaft E, and F the usual diffusing ring surrounding the impeller. The impeller D is shown as of a common inclosed type having the side walls 11 and vanes 12 extending between the side walls, and on opposite sides of the impellers are chambers 13 which may be quite deep chambers, as shown, or only shallow spaces between the impeller walls and the casing. These chambers 13 extend from the outer edge of the impeller inward to the running joints 1 which are formed between shoulders on the impeller and on the casing. Instead of making these chambers 13 of the same radial dimensions, as usual, so that the pressure surface in these chambers on opposite sides of the impeller is equal, I make the chamber on one side, and preferably the front or suction side of the impeller, as shown, of greater radial dimensions than that on the other side of the impeller, so that a larger surface on the impeller is exposed to the pressure in the chamber 13 on the suction side of the impeller, thus securing a constant excess of pressure tending to move the impeller to the right in the drawings.

I oppose this pressure excess by pressure from an outside source as follows:—At the back of the impeller is a balancing chamber 100

15 which connects through passages 17 with a circular chamber 18 in the casing, into which liquid under the desired pressure is introduced through pipe 19 controlled by a cock 20, the pressure on the rear side of the impeller opposed to the constant excess of pressure on the other side thus being regulated as desired. Such a balancing chamber may be used without provision for circulating the liquid between bearing surfaces to reduce friction and wear, but preferably, as in the construction shown, the chamber 15 is inclosed by the bearing surfaces on the back of the impeller and the bearing ring 14, and the space outside the bearing surfaces is connected with the impeller by passages 16 through the impeller. The liquid from pipe 19 thus passes between the bearing surfaces to the impeller and forms a liquid anti-friction bearing. The form and size of the chamber 15 may be varied according to the result desired, and for the anti-friction bearing it is necessary only that the surface of the impeller exposed to pressure therein shall be sufficient to press the impeller away from the bearing ring so as to permit the liquid to pass between the impeller and ring. The circular chamber 18 is not essential but any suitable connection constructed to supply liquid from the pipe 19 to chamber 15 may be used.

The invention is shown as applied to a pump having only a single impeller, but it will be understood that each impeller of a multi-stage pump may be similarly formed to secure an excess of pressure on one side and balance this by pressure from an outside source on the opposite side, and to provide the liquid bearing, if desired.

40 The circulation of liquid from the chamber 15 to the passages 16 between the bearing surfaces on the back of the impeller and the bearing ring 14 not only forms a liquid anti-friction bearing for the impeller, but, 45 as the pressure of the liquid passing through this annular space varies with its velocity, the slight sidewise movement of the impeller under varying side pressures automatically varies the pressure on the back of the impeller. Thus, if the running conditions of the impeller change so that the excess of pressure moves the impeller toward the bearing ring 14, this will reduce the space between the ring and the impeller and 50 throttle the circulating liquid so as to increase the pressure on the back of the impeller and thus balance the impeller under the new running conditions. Similarly, if 55 excess of pressure on the back of the impeller moves the impeller away from the bearing ring 14, this will increase the width of the narrow space between the impeller and the bearing ring 14 through which the 60 circulating liquid passes, and reduce the

pressure of this liquid on the back of the impeller to balance the pump. It will be seen also that in the construction shown, the balancing surfaces between the impeller D and bearing ring 14 are brought comparatively near the shaft. This is desirable as it reduces friction and wear from resistance to movement between the balancing surfaces, such resistance acting at a small leverage on the shaft.

It will be understood, also, that the invention is not to be limited to the particular form or construction of the pump shown, but that the invention is applicable generally in centrifugal, turbine and similar pumps with inclosed impellers, and may be embodied in different forms.

What I claim is:—

1. In a centrifugal, turbine or similar pump, an inclosed impeller having its outside surface exposed to delivery pressure larger on the suction side of the impeller than on the other side to secure a constant excess of pressure on the suction side of the impeller, in combination with a balancing chamber on the opposite side of the impeller, passages connecting said balancing chamber with the impeller, and means for supplying liquid to said balancing chamber under pressure greater than the pressure at the point where said passages connect with the impeller.

2. In a centrifugal, turbine or similar pump, an inclosed impeller having its outside surface exposed to delivery pressure larger on the suction side of the impeller than on the other side to secure a constant excess of pressure on the suction side of the impeller, in combination with a bearing disk on the opposite side of the impeller having a chamber between it and the impeller and an annular bearing inclosing the chamber, passages outside the bearing surface connecting with the impeller, and means for supplying liquid to said chamber under pressure to balance the excess of delivery pressure and form a liquid bearing for the impeller.

3. The combination with the inclosed impeller D having the chamber 18 on the suction side of the impeller of greater radius than on the opposite side, bearing ring 14 on the back of the impeller inclosing balancing chamber 15, openings 16 through the impeller connecting the impeller with the space outside the bearing ring, and means for supplying liquid under pressure to said balancing chamber.

4. The combination with the inclosed impeller D having the chamber 18 on the suction side of the impeller of greater radius than on the opposite side, bearing ring 14 on the back of the impeller inclosing balancing chamber 15, openings 16 through the impeller connecting the impeller with the

space outside the bearing ring, chamber 18
and means for supplying liquid under pres-
sure to said chamber, and passages 17
through the ring 14 connecting chambers
5 15, 18.

In testimony whereof I have hereunto set

my hand, in the presence of two subscribing
witnesses.

JOHN J. BROWN.
